CLAIM

The ornamental design for a wick combustion device, as shown and described.

DESCRIPTION

FIG. 1 is a perspective view of a wick combustion device showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the wick combustion device in which the design is embodied that are not considered part of the claimed design.

1 Claim, 7 Drawing Sheets
